UNITED STATES PATENT OFFICE.

SIMON N. MENTEL, MARY A. MENTEL, AND GEORGE E. MENTEL, OF SPRINGFIELD, OHIO.

STOVE.

1,228,579.

Specification of Letters Patent. Patented June 5, 1917.

Application filed June 8, 1916. Serial No. 102,462.

To all whom it may concern:

Be it known that we, SIMON N. MENTEL, MARY A. MENTEL, and GEORGE E. MENTEL, citizens of the United States, residing at 5 Springfield, in the county of Clark and State of Ohio, have invented certain new and useful Improvements in Stoves, of which the following is a specification.

This invention relates to improvements in 10 stoves, and particularly to that type of stove employing gas as a fuel.

An object of the invention is to provide 15 a stove of this type which will be simple in construction, economical in manufacture and effective in use.

A further object of the invention is to 20 provide a construction whereby a perfect combustion is obtained so that any odor resulting from incomplete combustion is eliminated.

A further object of the invention is to 25 provide a construction whereby the side walls of the stove are subjected to the cooling effect of a current of fresh air, which air is thereby warmed and allowed to escape into the room.

In the accompanying drawings:—

Figure 1 is a front elevation of a stove 30 embodying our improvements with the front grating removed.

Fig. 2 is a section on the line 2—2 of Fig. 1.

Fig. 3 is a section on the line 3—3 of Fig. 1, with the addition of the grating.

In carrying out the invention, we employ 35 a main casing of which 1 represents the back, 2 the top, 3 the bottom and 4 and 5 the sides, the casing being completely open at the front. Located in the casing are a 40 series of walls constructed as a unit for the purpose of causing a circulation of the products of combustion and also of the fresh air, consisting of side walls 6 and 7, a top wall or hood 8, a vertically extending 45 slightly inclined rear wall 9 which terminates at a point below the hood 8 and also at a point above the lower edges of the side walls, and an inclined auxiliary rear wall 10 which extends from the hood 8 to 50 a point below and to the rear of the upper edge of the wall 9; the wall 9 being also located at a point well in front of the rear edges of the side walls 4 and 5.

The lower edge of the wall 10 extends to 55 a point in close proximity to the rear wall 1 of the main casing so that a passageway

will be formed between the respective walls 9 and 10 as indicated at 11, the wall 10 serving to protect the rear wall 1 from the heat at that point. Secured to and extending between the walls 6 and 7 is a U-shaped plate 12 which surrounds the lower edge of the wall 9 and is spaced therefrom so as to provide passageways 13 and 14. The forward side of this plate 12 extends in 60 close proximity to the burner 15, which is one of ordinary gas burning form, while the rear side of the plate 12 extends up between the walls 1 and 9.

The side walls 4 and 5 are provided with 65 laterally extending flanges 16 and the side walls 6 and 7 have laterally extending side flanges 17 which overlap the flanges 16, these flanges not only providing the point of attachment for the front grating 18 70 (shown only in Fig. 3) but also serving to hold the interior walls in proper position in the main casing; the top 2 and bottom 3 of the main casing also having laterally extending flanges 19 to which the grating 75 18 is also secured.

In the operation of the device the heated 80 products of combustion pass upwardly along the front of the wall 9, which is covered with asbestos fiber, and thence through the 85 passageway 11 between the walls 9 and 10 and down between the walls 1 and 9 and thence through the passageways 14 and 13 where they are brought again in intimate 90 relation with the flame of the burner so that all products of combustion will be consumed.

The walls 6 and 7 terminate at points 95 above the bottom 3 and below the top 2 and are also spaced from the walls 4 and 5 so that an air passageway is provided between the walls 4 and 6 and walls 5 and 7, as indicated at 20, so that there will be a circulation of cool air between these walls which escapes at points 21 just above the 100 hood 8, this air not only serving to cool the side walls 4 and 5 but, becoming warm during its passage between the walls, is discharged in a more or less heated condition 105 into the room.

All of the walls are preferably constructed of sheet metal, the hood and wall 10 being covered with asbestos fiber like the wall 9 and the interior of the walls 4 and 5, the top 2 and flanges 16, 17 and 19 with 110 asbestos boards (not shown).

The burner 15 has at each end a down-

wardly extending lug 23 which lugs fit in loops 22 on the interior of the walls 6 and 7 so that the burner may be easily removed when desired.

5 From the foregoing description it will be seen that a gas burning stove is provided which is extremely simple in arrangement and number of parts employed; also one in which the products of combustion will be 10 circulated continuously before the flame of the burner until entirely consumed so that no unpleasant odors will result and the necessity of connecting the stove with a flue obviated.

15 The construction is also such that the parts of the stove may be readily removed for repairs or other purposes, it only being necessary to remove the fastening devices which secure the front grating in position, 20 after which the burner and interior baffle walls may be easily removed from the main casing.

25 The stove may be installed in a fire place or in the wall of the room if desired or may be provided with a base and legs so that it can be set at any convenient point in the room.

Having thus described our invention, we claim:—

30 1. In a stove, a main casing, a main baffle wall located in said casing having passageways above, to the rear and below the same, a gas burner located in front of said baffle wall with the gas outlets thereof above 35 the lower edge of said wall, and an auxiliary wall located between said baffle wall and said burner so as to form a continuation of the passageway beneath said baffle wall, the upper edge of said auxiliary wall 40 extending to a point in close proximity to the gas outlet openings.

2. In a stove, the combination with a main casing, a main baffle wall therein, a hood above said wall, said main baffle wall 45 having passageways between the upper edge thereof and said hood, to the rear of the same and beneath the same, a gas burner in said casing in front of said main baffle with the gas outlet portions thereof arched above the lower edge of said main 50 baffle wall, and an auxiliary wall located between said burner and said main baffle wall so as to form a continuation of the passageway beneath said main baffle wall, the upper edge of said auxiliary wall being 55 located at a point in close proximity to the gas outlet portion of said burner.

3. In a stove, a main casing, a burner therein, a main baffle wall therein, a 60 U-shaped plate embracing the lower edge

of said baffle wall but spaced therefrom, said baffle wall also having passageways about the upper edge thereof and to the rear of the same communicating with said passageways formed by said U-shaped plate, the passageways formed by said plate extending to a point in close proximity to the burner. 65

4. In a stove, a main casing, a main baffle wall therein, a hood above said baffle wall, an auxiliary baffle wall extending from said hood to a point below the upper edge of said main baffle wall so as to provide a passageway about the upper edge of said main baffle wall, said main baffle 70 wall and the rear of said casing forming a passageway back of said main baffle wall, a gas burner extending across and in front of said main baffle wall with the gas outlet portion thereof above the lower edge 75 of said wall, and a second auxiliary baffle wall between said burner and main baffle wall to form a continuation of the passageway beneath said main baffle wall, the passageway between said second auxiliary wall 80 and said main baffle wall being extended to a point in close proximity to the gas outlet openings of said burner. 85

5. In a stove, a main casing, a burner therein, a main baffle wall, a hood above 90 the upper edge of said wall, and an auxiliary baffle wall extending from said hood to a point to the rear of and below the upper edge of said main wall, a U-shaped plate embracing the lower edge of said 95 main wall but spaced therefrom, said baffle walls, hood and U-shaped plate forming passageways which extend about the upper edge, behind and around the lower edge of said main baffle wall to a point in proximity 100 to said burner.

6. In a stove, a main casing open at the front, a removable burner therein, inner side walls forming air spaces between the same and the sides of said main casing, a 105 main baffle wall forming a passageway between the same and the rear wall of said main casing, auxiliary walls also forming passageways about the upper and lower edges of said main baffle wall, said main 110 baffle wall, auxiliary walls and inner side walls being connected together as a unit and removable from said main casing.

In testimony whereof, we have hereunto set our hands this 5th day of June 1916.

SIMON N. MENTEL.

MARY A. MENTEL.

GEORGE E. MENTEL.
